ASH TRAY

Paul R. Bickford, Chicago, Ill.

Application January 26, 1959, Serial No. 54,307

Term of patent 3½ years

(Cl. D85—2)

Fig. 1.

Fig. 2.

Fig. 3.

Fig. 4.

Fig. 5.

Fig. 6.

Fig. 7

Fig. 1 is a top plan view of an ash tray embodying my new design;

Fig. 2 is a side elevational view;

Fig. 3 is a top perspective view;

Fig. 4 is a top plan view of the bottom part;

Figs. 5 and 6 are perspective views of one of the segments and the center bowl; and

Fig. 7 is a perspective view of the bottom of my ash tray.

I claim:

The ornamental design for an ash tray, substantially as shown.
